(57) **CLAIM**

The ornamental design for headband including an earshaped ear pad, as shown and described.

DESCRIPTION

FIG. 1 is a left side perspective view of the headband including an earshaped ear pad;

FIG. 2 is a right side perspective view of the headband including an earshaped ear pad;

FIG. 3 is a front view of the headband including an earshaped ear pad;

FIG. 4 is a rear view of the headband including an earshaped ear pad;

FIG. 5 is a left side view of the headband including an earshaped ear pad;

FIG. 6 is a right side view of the headband including an earshaped ear pad;

FIG. 7 is a top of the headband including an earshaped ear pad; and,

FIG. 8 is a bottom of the headband including an earshaped ear pad.

1 Claim, 8 Drawing Sheets
